[57] CLAIM

The ornamental design for a wall-mounted drawer and shelf combination, as shown and described.

DESCRIPTION

FIG. 1 is a perspective view of a wall mounted drawer and shelf combination embodying my new design; FIG. 2 is an enlarged left side elevational view thereof, the side opposite being a mirror image;

FIG. 3 is an enlarged front elevational view thereof;

FIG. 4 is an enlarged top plan view thereof;

FIG. 5 is an enlarged bottom plan view thereof.
